Attorney

UNITED STATES PATENT OFFICE.

JOHN PICKRELL, OF LOUISVILLE, KENTUCKY.

REFRIGERATOR.

Application filed November 22, 1924. Serial No. 751,655.

The invention provides a refrigerator designed chiefly for domestic use and which utilizes the ice to the best possible advantage in the cooling of the interior of the refrigerator so as to preserve the contents.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification—

Figure 1 is a front view of a refrigerator embodying the invention,

Figure 2 is an enlarged sectional view on the line 2—2 of Figure 1, and

Figure 3 is a sectional view on the line 3—3 of Figure 2.

Corresponding and like parts are referred to in the following description and designated in the several views of the drawings by like reference characters.

The numeral 10 designates the body of the refrigerator which consists of a box or chest of any approved construction, the same being closed at its front by double doors 11 which are made secure by pivoted fastenings 12. An opening is formed centrally within the top of the box or chest and a tapering receptacle 13 of sheet metal is suspended within the opening and constitutes a container for ice, the bottom 14 being upwardly deflected so as to shed the water to a drain pipe 15. Removable cones or plates 16 are disposed within the receptacle 13 at different elevations and serve as baffles to direct the water from the melting ice outwardly against the sides of the receptacle 13 so as to cool the same and these plates furthermore may receive and support the ice. The receptacle is spaced from the walls of the box or chest as indicated most clearly in Figure 3, thereby insuring a thorough cooling of the air and the utilization of a maximum degree of coldness resulting from the

melting of the ice, the water of which is directed against the walls of the receptacle which are thereby thoroughly cooled. The space surrounding the receptacle 13 may be utilized for the storage of food to be kept cool and the receptacle may be of any construction and outline so long as it tapers from top to bottom and is disposed to leave a space between its sides and the opposing sides of the box or chest.

In charging the refrigerator, the cones 16 are removed and cracked ice is then placed in the bottom. Thereupon the lower cone 16 is placed in position, and so on until the receptacle is filled with broken ice. As the ice melts, the partitions or cones withhold and prevent all the ice from sinking to the bottom and as the ice melts the water would trickle down the walls of the receptacle past the edges of the cones or partitions. In this manner a large surface will be cooled by the film of drip water and the ice in part being supported above the bottom will be in a position to produce a greater cooling effect than if held on the bottom alone.

What is claimed is:—

1. An ice receptacle for a refrigerator having its bottom deflected upwardly from its edges to its center, a substantially conical ice supporting means within the receptacle spaced above the bottom, the base of said supporting means being of slightly less cross sectional area than the interior of the receptacle in the corresponding plane whereby water is adapted to trickle down the wall of the receptacle, said supporting means being displaceable to facilitate the placing of ice below the same.

2. An ice receptacle for a refrigerator having an upstanding substantially conical bottom adapted to support ice, an upset substantially conical plate above said bottom of slightly less cross sectional area than the interior of the receptacle in the corresponding plane whereby water is adapted to trickle down the wall of the receptacle, said plate being removable for the positioning of ice below the same and on said bottom.

In testimony whereof I affix my signature.

JOHN PICKRELL.
